(57) **CLAIM**

The ornamental design for a multi-use organizational card caddy, as shown and described.

DESCRIPTION

FIG. 1 is a top, left perspective view of the first embodiment of the multi-use organizational card caddy showing my new design;

FIG. 2 is a front elevational view of FIG. 1;

FIG. 3 is a rear elevational view of FIG. 1;

FIG. 4 is a left side elevational view of FIG. 1;

FIG. 5 is a bottom plan view of FIG. 1;

FIG. 6 is a top plan view of FIG. 1;

FIG. 7 is a left perspective view of FIG. 1 shown in open position;

FIG. 8 is a left side elevational view of FIG. 7; FIG. 9 is a front elevational view of FIG. 7; FIG. 10 is a rear elevational view of FIG. 7; FIG. 11 is a bottom plan view of FIG. 7; FIG. 12 is a top plan view of FIG. 7; FIG. 13 is a left perspective view of a second embodiment of the multi-use organizational card caddy; FIG. 14 is a front elevational view of FIG. 13; FIG. 15 is a rear elevational view of FIG. 13; FIG. 16 is a left side elevational view of FIG. 13; FIG. 17 is a bottom plan view of FIG. 13; FIG. 18 is a top plan view of FIG. 13; FIG. 19 is a left perspective view of FIG. 13 shown in open position; FIG. 20 is a left side elevational view of FIG. 19; FIG. 21 is a front elevational view of FIG. 19; FIG. 22 is a rear elevational view of FIG. 19; FIG. 23 is a bottom plan view of FIG. 19; FIG. 24 is a top plan view of FIG. 19; FIG. 25 is a left perspective view of a third embodiment of the multi-use organizational card caddy; FIG. 26 is a front elevational view of FIG. 25; FIG. 27 is a rear elevational view of FIG. 25; FIG. 28 is a left side elevational view of FIG. 25; FIG. 29 is a bottom plan view of FIG. 25; FIG. 30 is a top plan view of FIG. 25; FIG. 31 is a left perspective view of FIG. 25 shown in open position; FIG. 32 is a left side elevational view of FIG. 25; FIG. 33 is a front elevational view of FIG. 25; FIG. 34 is a rear elevational view of FIG. 25; FIG. 35 is a bottom plan view of FIG. 25; and, FIG. 36 is a top plan view of FIG. 25.

The broken line showing of fasteners and cards inside the caddy are included for the purpose of illustrating environment and form no part of the claimed design.
